UNITED STATES PATENT OFFICE

JAMES S. REID, OF CLEVELAND, OHIO, ASSIGNOR TO THE EATON AXLE & SPRING COMPANY, OF CLEVELAND, OHIO, A CORPORATION OF OHIO

CLOSURE

Application filed September 7, 1929. Serial No. 390,866.

This invention relates to closure devices, and more particularly to an improved form of cap or closure, such as may be used on the filler necks of automobile gas tanks, radiators and the like.

An object of this invention is to provide a closure having improved and simplified means for connecting the locking member to the closure body.

Another object of this invention is to provide a closure having improved means for connecting the locking member to the closure body, which will permit the locking member to be readily removed and replaced when damaged.

The invention may be further briefly summarized as consisting in certain novel combinations and arrangements of parts herein-after described and set out in the appended claims.

In the accompanying sheet of drawings forming a part of this application,

Figure 1 is a bottom plan view of my improved closure.

Figure 2 is a sectional view taken on line 2-2 of Fig. 1.

Figure 3 is a sectional view taken on line 3-3 of Fig. 1.

Figure 4 is a top plan view of the filler neck; and

Figure 5 is a sectional view taken on line 5-5 of Fig. 4.

The closure device of my invention is of the quick detachable bayonet type adapted to be applied to the opening of a filler neck and releasably locked on the filler neck by relative rotation between the latter and the closure.

In the drawings illustrating the closure device of my invention, I show a tubular filler neck 10, having an annular base flange 11 by means of which the neck may be secured to a fluid container 12. At its outer end the wall of the filler neck is bent to provide the laterally extending flange 13, which serves as a gasket seat. Diametrically opposed portions of the laterally extending flange 13 are turned inwardly to provide the outer end of the filler neck with the depending flanges 14. The inner edges of these depending flanges are

shaped to provide the inclined cam portions 15, which terminate at one end in the dwells or recesses 16 formed adjacent the stops 17, and at the other end terminate in the openings 18, which are formed in the laterally extending flange 13 to afford access to said cam surfaces.

The cap or closure which is applied to the outer end of this filler neck comprises a closure body 19, and a locking member 20 carried by the closure body for releasable locking engagement with the cam portions of the filler neck.

The closure body itself may assume various shapes, and may be formed of two or more parts secured together in any suitable manner. In this instance, however, the closure body 19 is made up of sheet metal stampings comprising a rounded top or outer part 20, and bottom or inner part 21 constructed in the form of a plate provided with a central depending boss 22. The outer part and the inner part are assembled to provide a space therebetween and are permanently secured together by beading the annular portion 23 of the outer part around the annular portion 24 of the inner part. The inner part is preferably provided with an axially extending annular rib 25 which presses the gasket 26 against the outer end of the filler neck to provide an efficient seal between the closure and the neck when these parts are releasably locked together.

The locking member 20, which secures the closure to the filler neck, in this instance, is formed with a body portion 27 having laterally extending resilient locking fingers 28. When the closure is applied to the filler neck the locking fingers enter the openings 18, and upon rotation of the closure relative to the neck the resilient fingers engage and ride upon the cam portions 15 until they reach the dwells 16, whereupon further movement is arrested by the stops 17. For securing this locking member to the closure body I provide a retaining member 29 which is constructed in the form of a cup-shaped stamping adapted to fit over the central depending boss formed on the inner part 21. Diametrically opposed openings 30 are pro-

vided in the wall of the retaining member through which the resilient fingers of the locking member extend. The bottom wall of the retaining member is preferably provided with a flat central portion which engages the under surface of the locking member and presses the latter against the bottom wall of the central boss of the inner part to thereby hold the locking member in proper position with respect to the closure body. For securing the retaining member to the closure body I have provided the side wall of the central boss of the inner part with circumferentially spaced laterally extending lugs 31 which are engaged by correspondingly arranged circumferentially spaced recesses 32 formed in the side wall of the retaining member. The engagement of the recesses 32 with the lugs 31 prevents rotation of the retaining member and of the locking member about the axis of the boss when the closure is rotated on the filler neck, bringing the locking member into engagement with the cam portions of the neck. The body portion of the locking member, as shown in Fig. 1, is wider than the openings in the walls of the retaining member, through which the locking fingers extend, so that endwise displacement of the locking member is prevented by the shoulders 33.

In assembling the retaining member upon the central boss of the inner part the resiliency of the metal causes the depressions 32 to snap over and firmly engage the spaced lugs, thereby clamping the locking member between the bottom wall of the retaining member and the bottom wall of the central boss. The use of the retaining member 29 for securing the locking member to the closure body permits these parts to be more easily assembled than if the locking member were riveted or otherwise secured to the body; and furthermore by this arrangement it will be readily seen that the retaining member, if desired, can be pried loose from the central boss when replacement of the locking member becomes necessary.

While I have shown and described the apparatus of my invention in a detailed manner, it should be understood, however, that I do not intend to limit myself with the precise details shown and described but regard my invention as including such changes and modifications as do not involve a departure from the spirit of my invention and the scope of the appended claims.

Having described my invention, I claim:

1. A closure for a tubular member comprising, a body having a central boss provided with circumferentially spaced lugs, a locking member for releasably holding said closure on said tubular member, and means for securing said locking member to said body, said means being provided with spaced

recesses arranged for snap engagement with said lugs.

2. A closure for a tubular member comprising, a body having spaced lugs thereon, a locking member for releasably holding said closure on said tubular member, and a retaining member for securing said locking member and said body together, said retaining member having correspondingly arranged parts for cooperation with said lugs. 70

3. A closure for a tubular member comprising, a body having a depending central boss, a locking member for releasably holding said closure on said tubular member, and means for securing said locking member to said body including laterally extending lugs on said boss, and a member fitted on said boss and having depressions in the wall thereof arranged to receive said lugs. 75

4. A closure for a tubular member comprising, a body having a depending portion, a locking member for releasably holding said closure on said tubular member, a retaining member arranged to fit over said depending portion for holding said locking member 85 in position with respect to said body, and spaced lugs on said depending portion adapted to cooperate with correspondingly arranged recesses in said retaining member for holding the latter on said depending portion. 85

5. A closure for a tubular member comprising a body having a depending part, a locking member for releasably holding said closure on said tubular member, and means for holding said locking member in position 100 with respect to said body comprising a retaining member adapted to fit over said depending part and secured thereto by snap engagement between portions of said depending part and portions of said retaining member. 105

In testimony whereof, I hereinto affix my signature.

JAMES S. REID.
